(74) Attorney, Agent, or Firm — Thomas W. Galvani, P.C.; Thomas W. Galvani

CLAIM

The ornamental design for a whole body blanket, as shown and described.

DESCRIPTION

FIG. 1 is a top front perspective view of a whole body blanket shown in accordance with our new design; FIG. 2 is a bottom front perspective view of the whole body blanket shown in FIG. 1; and

FIG. 3 is a rear elevation view of the whole body blanket shown in FIG. 1;

FIG. 4 is a top front perspective view of a whole body blanket shown in accordance with our new design;

FIG. 5 is a bottom front perspective view of the whole body blanket shown in FIG. 4; and

FIG. 6 is a rear elevation view of the whole body blanket shown in FIG. 4;

FIG. 7 is a top front perspective view of a whole body blanket shown in accordance with our new design;

FIG. 8 is a bottom front perspective view of the whole body blanket shown in FIG. 7; and,

FIG. 9 is a rear elevation view of the whole body blanket shown in FIG. 7.

The features shown in broken lines illustrate portions of the article which form no part of the claimed design.

1 Claim, 9 Drawing Sheets
